(57) **CLAIM**

The ornamental design for a controller for computer, as shown and described.

DESCRIPTION

FIG. 1 is a front side perspective view of a first embodiment of a controller for computer showing our new design; FIG. 2 is a back side perspective view thereof;

FIG. 3 is a front view thereof;

FIG. 4 is a back view thereof;

FIG. 5 is a top view thereof;

FIG. 6 is a bottom view thereof;

FIG. 7 is a right view thereof;

FIG. 8 is a left view thereof;

FIG. 9 is a front side perspective view of a second embodiment of a controller for computer showing our new design; FIG. 10 is a back side perspective view thereof;

FIG. 11 is a front view thereof;

FIG. 12 is a back view thereof;

FIG. 13 is a top view thereof;

FIG. 14 is a bottom view thereof;

FIG. 15 is a right view thereof; and,

FIG. 16 is a left view thereof.

The broken lines shown in the drawings depict portions of a controller for a computer and form no part of the claimed design.

1 Claim, 16 Drawing Sheets
